NEWSPAPER VENDING MACHINE

Samuel Leschin, New York, N. Y., assignor to International Vending Machine Corporation, New York, N. Y., a corporation of New York

Application February 2, 1945, Serial No. 575,746

2 Claims. (Cl. 312—51)

1

This invention relates generally to an apparatus for dispensing newspapers and the like, and more particularly to a dispensing apparatus whose operation is coin controlled.

One of the objects of my invention is an improved arrangement whereby the insertion of a proper coin and the operation of a control lever will eject a newspaper and also return one or more smaller coins which represents the difference between the price of the paper and value of the inserted coin.

Another object of the invention is an improved arrangement whereby the inserted coin will be returned when the reservoir is empty.

One of the features of the invention is an arrangement which functions uniformly regardless of the number of papers contained in the machine.

The general object of my invention is the provision of a simple and efficient arrangement for vending newspapers.

For the attainment of these objects and such several other objects as may hereinafter appear or be pointed out, I have illustrated an embodiment of my invention in the drawings wherein:

Figure 1 is a perspective view of the disclosed embodiment;

Figure 2 is a horizontal section taken on line 2—2 of Figure 1 looking in the direction of the arrows;

Figure 3 is a vertical section taken on line 3—3 of Figure 2;

Figure 4 is a section taken on line 4—4 of Figure 1;

Figure 5 shows in section the lower portion of the mechanism of Figure 4 immediately after discharge of a newspaper;

Figure 6 is a section through the newspaper ejector mechanism;

Figure 7 is a section taken on line 7—7 on Figure 6; and

Figure 8 is an enlarged view of a detail;

Figure 9 is a top view of the pusher mechanism;

Figure 10 is a cross section centrally through the pusher mechanism of Figure 9;

Figure 11 is a section like Figure 10, showing the pusher forced inwardly; and

Figure 12 is a perspective view of a coin packet.

The vending machine casing is shown in Figure 1. It is comprised of a front wall 10, rear wall 11, and side walls, top and bottom, to define a container for the operating mechanism and the stack of newspapers to be operated upon thereby.

2

The opening 12 receives the coin whereby the vending operation is effected and this coin is returned through opening 13 when the supply of newspapers has been exhausted. The relatively larger and horizontally elongated mouth 14 which opens into trough 15 permits the removal of a newspaper moved into the trough from a stack upon the insertion of a coin and the operation of a mechanism shortly to be described. The casing is shown as provided with the depressed space 16 into which extends the outer end 17 of the plunger whose operation can be effected to discharge a newspaper into the trough 15 only after a proper coin has been inserted in the opening 12.

Upon reference to Figure 2 which shows the interior of the casing as seen from above, it will be observed that the relatively narrow section at the right contains the operating mechanism and the remaining and relatively wider section contains the newspaper stack, and reference will now be made to Figure 3 which shows a vertical section through front and rear walls 10 and 11, wherein is shown platform 20 upon which the newspapers are stacked flat to form a vertically extending file or stack, the platform being dimensioned to the dimensions of the newspapers. This platform is inclined upwardly forwardly, that is in the direction of the front wall 10, for the reasons that will shortly be pointed out. The platform is elevated above the bottom of the casing to a level which approximates the bottom wall of the depressed space 16 in the front wall 10 of Figure 1, and terminates at its front a substantial distance short of the front wall 10 to leave a substantial space between it and the front wall, within which space there is the aforementioned trough 15 preferably although not necessarily shaped as shown, my invention contemplating that the mechanism to be described, move the topmost paper from the stack in the direction of the front wall so that it drops into the trough 15 in about the position shown in dotted lines of the paper P in Figure 3. This trough opens into the mouth or opening 14 whose size is such that the hand can be inserted thereto and paper removed from the trough therethrough.

A coin inserted into the opening 12 in the front wall is passed through a mechanism generally termed a slug rejecter which tests the coin for magnetism, weight, and size characteristics and disposes of it if it fails to meet the requirements in all three respects, in a direction other than for controlling the operation of the machine as

hereinafter to be set forth. A coin accepted by the slug rejector is fed thereby into the stationary conically shaped coin hopper 30 which centers it at its bottom in a manner and for the purposes now to be described. The member 17 which forms the operating end of the plunger and is accessible for manual operation from outside the casing is secured at its inner end to the plunger proper 32 shown on an enlarged scale in Figures 9 and 10 of the drawing. This plunger is mounted for a manual push and pull reciprocation by handle 17 and overlies a fixed platform 33 immediately therebeneath (see Figure 4) and is provided with a circular opening 34 therethrough in which may be received a coin entered through front opening 12 and accepted by the slug rejector and passed thereby into the hopper 30 when the plunger is in its normal and retracted position of Figure 4 wherein opening 34 in the plunger registers with and is immediately beneath the bottom discharge mouth of hopper 30.

The platform 33 which underlies the plunger 32 is provided with a similar coin receiving opening 36, however so positioned that it registers with the opening 34 of the overlying plunger 32 only when the plunger is at its innermost position of Figure 5 at which position the coin is discharged from the plunger coin receiving opening 34 into and through the coin discharge opening 36 in the platform 33 and into a coin compartment (not shown).

Upon reference to Figures 9 and 10 of the drawings it will further be observed that the plunger 32 is slotted at 38 centrally diametrically of the coin receiving opening 34 of the plunger, the slot being directed inwardly that is toward the rear of the casing and that the plunger is also slotted at 39 to provide an end abutment wall 40.

The coin hopper 30 is secured to the frame of the machine in any preferred or desired manner as by extension 41 fastened to wall 42 to which is secured bracket 42¹ which carries the freely oscillating pintle 43 to which are secured the locking arm 44 and the releasing arm 45. The assembly 43, 44 and 45 form, in effect, a bell crank lever and function as will now be pointed out. The locking lever 44 projects into the slot 39 in the plunger and presents its front wall in the path of the plunger abutment wall 40 from which it is normally spaced a short distance as is shown in Figure 9 so that this arm 44 which is biased counterclockwise by spring 47 will assume a position wherein it will limit the inward push of plunger 32 to the short distance of its spacing from abutment wall 40 and prevent an inward throw of the plunger for a sufficient distance to operate the mechanism. The releasing arm 45, which is the other arm of the bell crank, extends into the diametrical slot 38 to present its lower or free end in the path of the coin c which has been entered into the circular opening 34 of the plunger. This end of arm 45 is curved on its outer face as shown at 46 and is so positionally related in level to that of the coin c that upon inward movement of the plunger the coin will engage this free end 46 and cam it clockwise and thus cause locking lever 44 to move clockwise and out of the path of the abutment wall 40.

It will be observed that the end 46 of the lever 45 is shown in Figure 10 as spaced a less distance from coin c than is the end of the lever 44 from abutment wall 40, so that the initial inward movement of the plunger will cause the coin carried forwardly therewith, to engage and move arms 45 and 44 clockwise and the latter out of the path

of abutment wall 40 before it can engage the end of locking arm 44. If, however, there is no coin c held in the opening 34 of the plunger, the abutment wall 40 will engage the straight end wall of arm 44 and lock the plunger 32 against further inward movement.

At the extreme inner end of the plunger 32 is the downwardly extending abutment flange 48 which may be of any preferred or desired character and which is illustrated in the drawings as secured to the lower face of the plunger and as projecting rearwardly therebeyond. The full inward movement of the plunger 32 permitted by the presence of a coin therein, will cause this abutment wall 48 to engage a roller 49 carried on the outer end of an arm 50 which is fixed to and extends outwardly from the lower end of a shaft or rod 51 mounted in top and bottom bearings 52 and 53 (see Figure 4) for free rotation about a vertical axis. Shaft or rod 51 is provided with a longitudinally outwardly extending key 55.

The assembly now to be described is carried by the shaft or rod 51 to freely gravitate downwardly thereon. This assembly comprises a member 56 shaped as shown in Figure 6 to engage the key 55 so that while it is free to slide along the rod, it is held to move angularly therewith. Flanges 57 which extend oppositely from the key engaging walls 56¹ and 56² secure the member 56 to a base member 58 in any preferred or desired manner, as by screws. A headed screw 61 secured to block 58 forms a pivot post about which the block 60 may oscillate about a horizontal axis. An arm or bar 62 is received through an opening in the block 60 (see Figures 4 and 6) with its inner end extending beyond the block and engaged by one end of the spiral spring 63, the other end of which is secured to a pin or screw 65 carried by member 56. The major length of arm or bar 62 extends to the other side of the block 60 and its front end 64, carrying article pick-up means, is hollow or tubular to receive therewithin the cylindrically contoured member 66 having its outer end 67 enlarged and extending beyond this hollow end as shown in Figure 6. This enlarged outer end is shown as seating on the outer end wall of this hollow end 64. A pin 68 engaged transversely through member 66 extends through slot 69 in the hollow end 64. Slot 69 extends circumferentially so that the end member 66, 68 can have a limited oscillation relatively to the bar or arm 62. A spiral spring 70 about arm 62 has one end engaged with pin 68 and the other end engaged with member 71, shown as a screw or threaded post secured to arm 62. Extending diametrically through the headed or enlarged end 67 is a pin 72 shown as cylindrical and locked in adjusted position as by threaded member 74. This pin 72 terminates in the pointed end 73.

From the description thus far given it will be understood that with a coin in position in the opening in the plunger 32, an inward push upon the handle end 17 will release the locking lever 44 to permit a full inward throw of the plunger and that in this throw the abutment wall 48 (Figure 4) will engage the roller 49 and oscillate the shaft or rod 51 to swing the pointed end 73 of the pin 72 counterclockwise from its full line position of Figure 2 to its dotted line position in that figure and in so doing will move the topmost newspaper engaged by pointed end 73, from off the stack and into the trough 15 (see Figure 3). The spring 63 functions to hold the arm 62 inclined downwardly as shown in Figure 4 and this, combined with the free downward gravitating movement permitted

the aforementioned assembly, holds the pointed end 73 at the front end 67 of arm 62 in contact with the top most newspaper. The assembly referred to will act in the manner set forth regardless of the height of the stack and as long as a single newspaper remains on platform 20, because the assembly always floats downward to engage the newspaper exposed at the top.

Reference has been made to the fact that the platform 20 is inclined upwardly toward the front wall (see Figure 3). The lever 62 moves the pointed pin 73 in a horizontal plane and the inclination of the newspapers incident to the inclination of the platform 20 will further assure the maintenance of the engagement of pin 73 until the paper has been discharged into the trough and also prevent the accidental movement by friction of a second newspaper.

I will here premise that the vending machine herein disclosed contemplates that the coin to be accepted by the coin rejector is of a larger denomination than the cost of the paper. I therefore make provision for the return of change for the difference. For example, assuming that the only coin acceptable for operating the machine is a nickel and the cost of the newspaper is 3¢, the apparatus is devised to return 2¢ in change. This provision comprises the following mechanism: in Figure 4 I show a vertically extending reservoir 80 whose relative position may be as in the sectional showing of Figure 2 wherein the reservoir is shown as generally oblong in cross section and contoured and dimensioned to receive in vertically stacked relation, flat packets 81 of the character shown in Figure 12 of the drawing. These packets may comprise only a flat board with a plurality of circular openings therein of the size to receive in the particular disclosure herein, one, two or three pennies. For the broad purposes of my invention these openings can extend through the packet since the coins will be held in each packet because of their stacked relation. As a result, a packet such as shown in Figure 12 can be employed to return either 1¢, 2¢, or 3¢ in change. The reservoir 80 has the bottom of its front and rear walls 82 and 83 cut away as shown in Figure 4 so that the access can be had to the lowermost packet through the bottom of the rear wall to eject that lowermost packet through the bottom of the front wall. The mechanism for ejecting the lowermost packet is shown in Figures 4 and 5 and comprises a bracket 84 extending upwardly from the innermost end of the plunger 32 and therefore movable with the plunger. A horizontally positioned rod 85 is secured to the bracket and extends therefrom in the direction of the front wall of the packet reservoir and carries an ejecting finger 86 which is secured to the rod 85 in any preferred or desired manner as by the sleeve 87 and the threaded securing member 88, so that the position of the sleeve 87 can be adjusted along the rod 85. Upon viewing Figure 5 wherein the operating plunger is shown as pushed in to its limit, the end of the finger 86 will be on the level with and to the rear of the lowermost packet 81, it being remembered that this inward push of the operating plunger has already ejected a paper into the trough as shown in Figure 3. The operator is now required to pull the plunger outwardly in order to get his change as can be seen by comparing Figure 5 which shows the initiation of this outward movement with Figure 4 which shows its completion, during which increment of movement, the finger 86 will have engaged this lowermost packet 81 and moved it to the left in Figure 4 and 75 and moved it to the left in Figure 4 and 75

through channel 89 (see Figure 5) and into the depressed space 16 in which the plunger handle 17 projects. It will be understood, therefore, that on the inward movement of the plunger 32 a newspaper is deposited in the trough and on the outward movement of this plunger, the coin packet is deposited in the depressed space 16.

Figure 5 shows the angular positions of the shaft 51 and of the parts carried thereby including the newspaper engaging arm 62 and the roller carrying arm 50, when the plunger 32 has been pushed inwardly to move the topmost newspaper into the trough. I will now explain an arrangement whereby this shaft 51 and the aforementioned parts carried thereby are returned to their normal position of Figure 4 upon outward retraction of the plunger to expel a coin carrying packet. This arrangement comprises a spiral spring 92 secured at one end to an inner frame at 93 and with its other end engaged with the outer end 94 of hooked rod 95 received and held in the bore of the enlarged portion 96 of rod 51 adjacent its upper end. This spring 92 oscillates shaft 51 clockwise as the plunger is withdrawn or pulled outwardly, which in turn swings arm 62 from its dotted line position of Figure 2 to which it has been moved by the inward push of the plunger back to its full line starting position of that figure. The extent of this return movement of shaft 51 and arm 62 is limited by arm 76 secured to arm 62 somewhat as shown in Figures 4 and 6 so that its end 75 will engage the back wall of the frame when arm 62 has reached the angular position shown in full lines in Figure 4.

Reference has been made to the limited oscillation permitted pin 68 in the circumferentially extended slot 69. Spring 70 biases the pin 68 clockwise as shown in Figure 7 to direct the pointed end 73 of pin 72 forwardly, that is in the direction of the forward throw of the arm 62 which will force the pointed end 73 into the topmost newspaper and maintain it in such engagement. The inclination of platform 20 cooperates to this end.

In the return swing of the arm 62 under the impulse of the spring 92, pin 73 will have a wiping engagement with the newspaper which is now on top without piercing or scratching it. The wiping engagement will be facilitated by the fact that the member 66 is free to oscillate in slot 69 (see Figure 7).

My invention contemplates further that the newspaper discharging operation of the plunger 32 be prevented when there is no newspaper on the platform upon insertion of a proper coin into front opening 12. An arrangement to this end is shown in Figures 2, 4, 5 and 8. This arrangement comprises a lever 100 comprised of an upper portion 100¹ shown as extending generally horizontal, a lower portion 100² also shown as generally horizontal and the intermediate inclined portion 100³ connecting the two. This lever 100 is mounted to oscillate about a horizontal pivot (not shown) which is disposed within the slug rejector casing, the pivot being located adjacent point 100¹. This oscillation is effected by member 103 which is carried by and reciprocates with rod 85. This member 103 has roller 104 at its upper end for free rotation and engaging beneath the intermediate portion 100³ when the plunger is fully retracted. When pivoted lever 100 is in its lowermost position of Fig. 4, a coin inserted in the machine passes through the slug rejector (if it be a good coin) and into hopper 30. This permits plunger 17 and slide 32 to be moved manually rearwardly and the paper delivered. When, however, the

outer end of lever 100 is in the elevated position of Fig. 5, a shutter (not shown) in the slug rejector causes the coin to be returned to the customer. Thus, it is necessary to provide means for retaining lever 100 in elevated position after the supply of papers has been exhausted, which means will now be described.

The inward push of the plunger carries with it the roller 104 to swing member 100 from its position in Figure 4 to its position in Figure 5 and it will be here stated that in this position of Figure 5 member 100 interposes a shutter into the normal path of the coin to the hopper 30, to divert the coin to the discharge opening 13 in the front wall of the machine and that in its position of Figure 4 this shutter is withdrawn from out of this path, to permit free passage of the coin to the hopper. This shutter element has not been shown in the drawing because it is not claimed herein as a feature of invention. I show in Figure 8 a lever 106 pivoted at 107 and having one arm or end 108 engaged beneath the lowermost newspaper of the stack, the other arm or end carrying an upstanding rod or bar 109, the lever 106 being biased normally to its dotted line positions of this figure by the weight of the member 109 but held to its full line position in Figure 8 by the weight of any newspaper or papers present on platform 20. Upon the discharge of the last paper from platform 20, this lever 106 will assume its dotted line position of Figure 8 to present the member 109 underneath the projection 110 which is carried by and extends laterally from portion 100² of the member 100 as shown in Figure 2 so that the member 100 will be held in its elevated position of Figure 4 to divert the coin into the aforementioned discharge opening 13.

Having thus described my invention and illustrated its use, what I claim as new and desire to secure by Letters Patent is:

1. A machine for vending flat articles comprising a housing, a frame within the housing, a rearwardly and downwardly-inclined support upon which the articles to be vended are supported in superimposed relation, a trough for receiving the articles as they are delivered, one by one, from the support, and a horizontally-pivoted arm provided with pick-up means at its outer end for moving

the uppermost article in the pile into the trough, means for supporting the arm comprising a vertical post mounted in the frame adjacent one end of the inclined support, an arm support slidably mounted on the post for free gravitational movement thereon, the arm being pivotally mounted on the support adjacent its inner end, and spring means between the inner end of the arm and the support which urges the outer end of the arm downwardly relative to the support.

2. A machine for vending flat articles comprising a housing, a frame within the housing, a rearwardly and downwardly-inclined support upon which the articles to be vended are supported in superimposed relation, an open trough at the front of the housing for receiving the articles as they are delivered, one by one, from the support, and a horizontally-pivoted arm provided with pick-up means at its outer end for moving the uppermost article in the pile into the trough, means for supporting the arm comprising a vertical post mounted in the frame adjacent one end of the inclined support, an arm support slidably mounted on the post for free gravitational movement thereon, means for keying the support to the post and means for rotating the post through an arc, the arm being pivotally mounted on the support adjacent its inner end, and spring means between the inner end of the arm and the support which urges the outer end of the arm downwardly relative to the support.

SAMUEL LESCHIN.
